US0D1020721S

(12) **United States Design Patent** (10) **Patent No.:** **US D1,020,721 S**
(45) **Date of Patent:** **** Apr. 2, 2024**

(54) **PHONE CASE**

(71) Applicant: **Liyang Li**, Shaoyang (CN)

(72) Inventor: **Liyang Li**, Shaoyang (CN)

(73) Assignee: **Liyang Li**, Shaoyang (CN)

(**) Term: **15 Years**

(21) Appl. No.: **29/907,093**

(22) Filed: **Jan. 4, 2024**

(51) **LOC (14) Cl.** **14-03**

(52) **U.S. Cl.**

USPC **D14/250**

(58) **Field of Classification Search**

USPC D3/201, 218, 247, 249, 269; D13/107, D13/108, 118, 119; D14/217, 248, D14/250-253, 432, 440

CPC H04B 1/3888; H04M 1/0283; H04M 1/0202; A45F 2005/028; A45F 2200/0525

(57) **CLAIM**

The ornamental design for a phone case, as shown and described.

DESCRIPTION

FIG. 1 is a front perspective view of a phone case, showing my new design;

FIG. 2 is a rear perspective view thereof;

FIG. 3 is a second rear perspective view thereof, showing a state of use;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings illustrate the portions of the phone case which form no part of the claimed design.

1 Claim, 9 Drawing Sheets
